Co-pending U.S. Appl. No. 29/511,536; Applicant: Ashbee; Filed: Dec. 11, 2014.

Primary Examiner — Catherine Tuttle

(74) Attorney, Agent, or Firm — Greenberg Traurig, LLP

(57)

CLAIM

The ornamental design for a bottle, as shown and described.

DESCRIPTION

FIG. 1 is a front perspective view of a bottle showing our new design;

FIG. 2 is a front elevational view thereof;

FIG. 3 is a back elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in FIG. 7 are included for the purpose of illustrating a portion of the bottle that forms no part of the claimed design.

1 Claim, 6 Drawing Sheets(56)
